Fuller Box Co. Inc., North Attleboro, Mass., a cor-
poration of Massachusetts

Application May 10, 1954, Serial No. 30,394

Term of patent 14 years

(Cl. D80—5)

To all whom it may concern:

Be it known that I, Virginia Ann King, a citizen of the United States, residing in North Attleboro, in the county of Bristol and Commonwealth of Massachusetts, have invented a new, original, and ornamental Design for a Display Box for Men's Jewelry, of which the following is a specification, reference being had to the accompanying drawing, forming a part thereof, in which:

The figure is a view in perspective of a display box for men's jewelry showing my new design, certain parts being lined to indicate contrasting colors.

The broken lines showing is for illustrative purposes only.

I claim:

The ornamental design for a display box for men's jewelry, substantially as shown and described.
